R. W. BAYLOR, OF NORFOLK, VIRGINIA.

Letters Patent No. 94,547, dated September 7, 1869.

IMPROVED RAILWAY-CAR COUPLING.

The Schedule referred to in these Letters Patent and making part of the same.

To all whom it may concern:

Be it known that I, R. W. BAYLOR, of Norfolk, in the county of Norfolk, and State of Virginia, have invented certain new and useful Improvements in Car-Couplings; and I do hereby declare that the following is a full, clear, and exact description of the same, reference being had to the accompanying drawing, and to the letters of reference marked thereon, making part of this specification, in which—

Figure 1 is a top view of a draw-head, with my improvement attached.

Figure 2 is a horizontal sectional view.

Figure 3 is a front view.

Figure 4 is an upper face view of the bottom plate.

Figure 5 is a horizontal sectional view of the double coupling-link.

Figure 6 is a bottom view of the draw-head.

Figure 7 is a view of the key.

The nature of my invention consists in constructing the draw-head with a movable bottom, so hinged that when left free, it falls, by its own weight, from its position parallel with the upper plate to one at an angle thereto.

This bottom is elevated and held in position by means of a rectangular bearing-plate, so connected with a rod or arm that passes up through the draw-head, that the revolving of the former shall give to the latter a circular sweep.

By this arrangement I am enabled at pleasure, by simply turning the rod, to bring the bearing-plate in a line with the bottom, or to throw the same in such position that they will each be entirely free of the other, when the bottom instantly falls.

The bottom plate has a recess on its upper face. In this recess works the free end of the coupling-catch or pin.

This catch or pin is pivoted in a suitable bearing on the inner surface of the top plate of the draw-head, and at such point and in such manner as to fall and rest against the forward face of the recess in the bottom plate.

Thus it will be observed that so long as the bottom plate is held up, a firm and secure bearing, and one that it cannot pass, is afforded the catch or pin, but so soon as the bottom is permitted to fall, the pin being left perfectly free, a draught is only required that is sufficient to move the same, to draw it instantly forward.

While the catch or pin, so long as the bottom is held in an elevated position, cannot be drawn forward beyond its line of bearing, still, owing to the form of the recess, its utmost freedom of movement in the opposite direction is allowed.

The slightest pressure of the coupling-link will readily elevate and push the catch or pin back, where

it is held until the passage of the head or end of the link, when the pin will instantly swing back to its former position, resting or bearing against the front face of the recess, and securely fastening the link.

By this simple and practical arrangement, one entirely free from all complicated mechanism, I am enabled to accomplish the two chief objects of my invention, viz., to furnish a device that, in coupling or connecting the cars, is purely automatic in its operation, and at the same time one which enables the brakeman, or other employé, to uncouple or disconnect the cars at pleasure, and with as much readiness and ease when the pin is subjected to a heavy draught, as when the same is entirely removed.

Another feature of my invention is found in the method by which the rod or arm, which is connected with the bearing that supports the bottom plate of the draw-head, is worked.

To the rod is permanently attached a ratchet-wheel, which, in connection with a spring-pawl, secures the rod at the desired points.

On the upper face of the ratchet-wheel are two short pins or stumps, which furnish bearing-surfaces for the key that moves the rod.

This key also works a bevelled plate that is secured to the ratchet.

Owing to the form of the bevel and the key, the moment you commence to turn the rod, the pawl is held free of the ratchet, and is retained in such position until a sufficient revolution of the rod is made to insure the necessary movement of the bearing-plate, and the consequent elevating or lowering of the bottom plate.

My invention also consists in constructing the catch or pin in the form of a reversed cross, which is so arranged as to work in the grooved bottom in such a manner that while it allows the necessary freedom of movement to the coupling-link, it at the same time retains the link in such position that it will not fall below the coupling-point.

My invention also consists in so combining a straight and reversed bent link that it can readily be made to accommodate itself to any cars, no matter what the difference of their height may be.

To enable others skilled in the art to make and use my invention, I will now proceed to describe its construction and operation.

A is the draw-head, which is constructed of any suitable material, and with the ordinary flaring or bell-shaped mouth.

The bottom A' of the draw-head, instead of being constructed in one piece with top and side plates, as is usual, is an independent piece, and hinged as seen at a.

It will be observed, by reference to fig. 2, that a

portion of the forward end of plate A' is cut away. This causes the entire blow, produced by the cars coming together, to be received by the top and sides of the draw-head, freeing entirely the hinged bottom of all undue strain.

The plate A' is formed with a circular groove or recess, B.

In this recess works the free end of the falling or adjustable coupling-catch or pin C.

This catch or pin C is pivoted in suitable bearings, e, arranged in the top plate, and is secured at such point that when it falls and occupies a perpendicular position, it rests and bears against the front face b of the groove B, and beyond which point it cannot pass or be drawn, so long as the bottom plate A' remains in the position shown in fig. 2. Still, owing to the form of the groove B, the utmost freedom of movement in the opposite direction or toward b' is allowed, the slightest pressure against the catch or pin C readily causing the same to swing back out of its line of bearing.

Thus it will be observed how easily, by the simple pressure of the link against the catch or pin C, it can be pushed back, so as to allow of the passage of the link, and how impossible it is for the link, after it has once passed, to be drawn out, unless the bottom plate is caused to fall.

The form of the catch or pin C is that of a reversed cross, as is clearly shown in fig. 3.

The great advantage possessed by this form of catch or pin is found in the fact that while it allows the link all the necessary play required, still at the same time, the end of the link, when free, is never permitted to fall below the coupling-point, which is most important in car-couplings, especially those that are intended to operate automatically.

The hinged bottom A' of the draw-head is held in position by means of a bearing-plate, D.

This plate D is constructed of metal, and is rectangular in form. It works in and is chiefly supported by a metallic bracket, D', which is secured to the under surface of one of the sides of the draw-head A.

This plate D is also, at d, permanently welded or otherwise firmly secured to a metallic rod or arm, E.

This rod E passes up through the draw-head, and is held by a nut, d'.

This nut d' can from time to time be tightened, and the looseness of the plate D, caused by wear, can be taken up.

To this rod E is permanently attached a ratchet-wheel, E'.

This ratchet E' is retained and held in proper position by means of a spring-pawl, e.

To this pawl e is secured a bevelled plate, e'.

On the upper face of the ratchet-wheel E' are permanently secured two stumps or bearing-pins, f f'.

F is the key, its form being clearly shown in fig. 7.

G is the combined coupling-link, and consists of two links, G¹ G², firmly welded together. The form of this combined link is clearly shown in fig. 5.

The operation is as follows:

The normal position of the draw-head A and the entire mechanism is clearly shown in fig. 2. The coupling-link G, on entering the draw-head, pushes back the catch or pin C, and retains the same in a slightly elevated angular position, until the curved end of the link G passes the catch C, when the latter in-

stantly falls in the opening of the link, and swings to its former position, having again its bearing against the face b of the recess B.

The cars are now securely coupled, and no amount of draught on the link G will free the same, so long as the plate D retains the bottom A' of the draw-head A in position. But so soon as the plate D is turned, the bottom A', having no longer any support, immediately falls, and the cars are instantly uncoupled.

This plate D is worked in the following manner:

The key F is placed on the head of the arm or rod E, and its flanged blade F' is caused to bear against the pin f. The end of the blade F' entering the bevel of the plate e' at x, forces the pawl e away from the ratchet E'. The key F can then easily turn the rod E, as, owing to the form of the bevel, the pawl e cannot come in contact with the ratchet E' until the point x' on the bevel-plate e' is reached, when the pawl e falls against one of the teeth of the ratchet E', and its further progress, as well as that of the rod E, is instantly arrested. But the revolution thus made by the rod E is exactly what is required to move the plate D from under the bottom A' out to the side of the draw-head, and nearly at right angles thereto.

It will be observed that this circular sweep of the plate D entirely frees the bottom A' of all support, and it will, consequently, fall by its own weight down to a point that will entirely free the end of the catch C, and permit the link G, without the slightest obstruction, to be drawn out.

The draught on the pin C having nothing to do with the movement of the plate D, it will readily be observed how easily it is to disconnect or uncouple the cars, no matter what the degree of draught at the time may be.

To elevate the bottom A', you have simply to apply the key F as before, and turn the same in the opposite direction, bearing against the pin f', instead of the pin f.

The compound coupling G allows cars of different heights to be coupled, the links not used passing under and above the draw-head, as the case may be.

Having thus fully described my invention, What I claim therein as new, and desire to secure by Letters Patent of the United States, is—

1. The draw-head A, when the same is provided with a hinged bottom, A', plate D, and rod E, when the whole is so combined and arranged as to operate substantially as described.

2. The bottom A', having a recess, B, and pivoted catch or pin C, when the same are so formed, combined, and arranged that they will operate substantially as described, as and for the purpose specified.

3. The rod E, ratchet E', having pins f f', spring-pawl e, and bevelled plate e'; when the same are so combined and arranged that they can be operated by a key, F, substantially as described.

4. The compound link G, when the same is constructed substantially as described.

In testimony whereof, I have signed my name to this specification, in the presence of two subscribing witnesses.

R. W. BAYLOR.
